UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

AMMONIA AND TAR RECOVERY PROCESS.

1,375,483.

Specification of Letters Patent. Patented Apr. 19, 1921.

Application filed August 21, 1919. Serial No. 318,903.

To all whom it may concern:

Be it known that I, JOSEPH BECKER, a citizen of the United States, residing in Pittsburgh, in the county of Allegheny and 5 State of Pennsylvania, have invented a new and useful Improvement in Ammonia and Tar Recovery Processes, of which the following is a specification.

This invention relates primarily to the 10 recovery of tar and of ammonia from producer-gas and has for its object the efficient production of a clean, dust-free and high-grade tar and of a clean, tar-free and dry ammonium sulfate that has a high content 15 of ammonia and is of the large crystal type and is produced with great economy of heat or steam and with simplicity and directness in the operation of the apparatus; the invention may also be applied to the 20 treatment of gas that is otherwise derived from the carbonization of coal, and may also have such other objects and results as are found to obtain in the processes hereinafter set forth and claimed.

25 In the accompanying drawings:

Figure 1 is a conventional diagram illustrating an embodiment of the invention in one arrangement of apparatus for practising its processes.

30 Fig. 2 is a key to the symbols employed in the various lines that show the connection between the apparatus indicated in Fig. 1.

Fig. 3 is a conventional diagram illustrating an embodiment of the invention in another arrangement of apparatus for practising its processes.

Fig. 4 is a key to the symbols employed in the various lines that show the connection between the apparatus indicated in 40 Fig. 3.

Fig. 5 is a conventional diagram illustrating an embodiment of the invention in still another arrangement of apparatus for 45 practising its processes.

Fig. 6 is a key to the symbols employed in the various lines that show the connection between the apparatus indicated in Fig. 5.

50 Fig. 7 is a conventional diagram illustrating an embodiment of the invention in still another arrangement of apparatus for practising its processes, the symbols employed in the various lines being the same

55 as the symbols employed in the other figures.

Referring now more particularly to Figs. 1 and 2 of the drawings:

There is indicated at 6, a gas-producer from which the hot evolved producer-gas passes through the gas line 7 to the electrical dust precipitator 8. The producer-gas entering this electrical precipitator is still at a very high temperature, about 450° C., and therefore it is still greatly superheated with respect to its water and tar, and these, 60 and its other vaporizable content, are carried as vapor into and through said precipitator 8. In said precipitator 8, the producer-gas flows in counter-current with water that enters said precipitator through 70 the water line 9, and, as a result of the heat interchange between the producer-gas and the water in said electrical dust precipitator 8, the water is converted into steam which passes to the steam-dome 10 of the 75 electrical dust precipitator 8 and thence flows out the steam line 11. In addition to cooling the producer-gas, the electrical dust precipitator 8 acts also to free the passing gas from dust and other solid impurities 80 in its current.

The gas, after having been cooled to about 250° C. passes through the gas line 12, still carrying its water and tar as vapor, to the water cooled disintegrator 13 which it leaves 85 at a temperature of about 90° C. At such temperature, the tar, approaching the character of a finely comminuted mist, has begun to be precipitated; and any tar so precipitated in the disintegrator is discharged 90 through the tar line 14 into a tar tank 15. A continuous supply of cooled water is introduced into the disintegrator 13 through the water line 16 and this water is thoroughly agitated with the gas in the disintegrator. The effect of the thorough agitation of the gas with the cooling water in the disintegrator is primarily to further clean such gas by precipitating any residue of dust or other solid impurities. 95

The partially cooled producer-gas, still carrying the major portion of its tar as vapor, emerges from the disintegrator 13 at a temperature of about 90° C. and passes through the gas line 17 to the electrical tar 105 precipitator 18 in which the residue of the tar in the gas will be precipitated; the clean tar so precipitated is discharged through the tar line 19 into the aforesaid tar tank 15.

The gas passes from said tar-precipitator 110

18 through the gas line 20 to the acid-washer ammonium sulfate disintegrator 21, which it enters at a temperature of about 90° C. In said acid-washer ammonium sulfate disintegrator, the ammonia is absorbed from the gas and the precipitation of ammonium sulfate from the resultant ammonia-charged acid solution is effected by means of the remaining super-heat in the gas. The acid solution is kept hot by the absorption reaction, so that there cannot be any diluting of the ammonia-absorbing acid-solution that is flowing through said acid-washer ammonium sulfate disintegrator; and, by reason of the super-heat remaining in the gas, water is absorbed from the ammonia-charged acid solution, thereby effecting the precipitation of ammonium sulfate directly in said disintegrator 21 and rendering unnecessary the employment of a separate saturation bath for the precipitation of the ammonium sulfate from the ammonia-charged acid-solution. The dew point of the gas may be regulated within the water-disintegrator 13 by regulating the quantity of water fed to the water-disintegrator through the water supply line 16, in such manner that the gas when it reaches the acid-washer ammonium sulfate disintegrator 21 has enough remaining super-heat to effect the precipitation of ammonium sulfate in said disintegrator 21. In any event, however, should the gas leave the water-disintegrator 13 at a temperature below that temperature effective for the precipitation of ammonium sulfate, the temperature of the gas may be raised in the electrical tar precipitator 18 by passing it in counter-current with steam flowing through said tar-precipitator. The steam may enter the tar-precipitator 18 through the steam line 50 and the waste steam may discharge through the waste steam line 51.

From the acid-washer ammonium sulfate disintegrator 21, the ammonia-free gas flows through the gas line 22 into the first-stage final-cooler 23, through which it flows in counter-current with warm water that enters such cooler at about 50° C. In this cooler, the gas is cooled to about 65° C., and to a great extent dehydrated, and thence passes, through the gas line 24 to the second-stage final-cooler 25, through which it passes in counter-current with cold water at about 25° C. and issues finally dehydrated and cooled to a temperature of about 25° C. The clean, cool and relatively dry gas is drawn off through the gas line 26 by the exhauster 27, and passes through said gas line 26 to the gas-holder 28 from which the gas may be forwarded through the supply-line 29 to any service it may be employed in.

The ammonium sulfate and such acid-solution as it may carry with it are drawn off from the disintegrator 21 through an ejector line 30 and pass over the drain-table 31, and

into the centrifugal drier 32 from which it is discharged and carried, in any preferred manner, to the storage pile of the by-product house. The ammonium sulfate discharged from the centrifugal drier 32 has the dry, clean and large crystal character, with high ammonia content, of the high-grade ammonium sulfate that may be derived from the saturator-processing of coke-oven gas.

The producer-gas from the producer, until it reaches the final coolers 23, 25, carries a great amount of water vapor and its volume in such super-heated condition is enormously greater than after it has been dehydrated and cooled in the final-coolers. In its dried and cooled condition, a far less volume is required to pass through the exhauster 27, and the exhauster is not required to be of impractically large dimensions.

The acid-solution from the drain-table 31 and also any acid-solution drained off from the centrifugal drier 32 is drawn through the acid-line 33 to the acid-pump 34 and thence is forwarded through the return acid-line 35 to the acid-washer ammonium sulfate disintegrator 21, which also receives fresh acid from the acid-tank 36. The returned acid-solution is still sufficiently heated to prevent cooling of the acid-solution that is receiving heat from the absorption reaction in said disintegrator 21. A continuous circulation of hot acid-solution is maintained through the disintegrator 21 and thence from the drain table 31 and centrifugal drier 32 back to said disintegrator 21.

The aforesaid first-stage final-cooler 23 receives its water at a temperature of about 50° C. and discharges it at a temperature of about 80° C.; such discharged hot water is forced through the hot-water line 37 by the hot-water pump 38 to the air-saturator tower 39. From the said air-saturator tower 39 the water issues cooled to a temperature of about 50° C. and is forced through the warm-water line 40, by the warm-water pump 41, to the said first-stage final-cooler 23 in which the ammonia-free producer-gas undergoes the first stage of its final cooling. The second-stage final-cooler 25, however, receives a continuous supply of fresh water, which is forwarded by the fresh water pump 42 through the fresh-water line 43 to said second-stage final-cooler 25; the drain from said cooler 25 discharges through the drain line 44.

The air that is charged with water-vapor and super-heated and led to the gas-producer 6 is drawn in from the outside through the fan 45 and thence is forwarded, through the air-line 46 to the aforesaid air-saturator tower 39, which it enters at a temperature of about 25° C. In this tower 39, the air, passing through the water introduced from the before-mentioned hot-water line 37, is heated and takes up water-

vapor and issues charged with water-vapor, at a temperature of about 80° C., and passes through the air-line 47 to the super-heater 48. In said super-heater 48, the air is 5 super-heated by passing it in counter-current with waste flue-gas, for example, stack-gas or waste hot gas from any suitable outside source.

In the super-heater 48, the air is super-10 heated to a very high temperature, and because of this fact, the saturation point of the air is raised enabling the air to carry considerably more water vapor. This water vapor is supplied from the steam-line 11 15 through which the steam generated in the aforesaid electrical dust precipitator 8 flows to the air-line 47 and mixes with the air before it enters the super-heater 48. The admixed steam has the further effect of 20 increasing the temperature of the air before it enters the said super-heater 48. By the employment of the electrical dust precipitator as a steam generator, the heat of the hot producer gas from the producer is 25 utilized to generate steam for charging the air before it enters the super-heater 48; this expedient renders unnecessary the employment of, or at least reduces the amount of, outside steam for charging the air. The 30 air laden with water-vapor and heated to a temperature of about 250° C. emerges from the super-heater 48 and passes through the air-line 49 to the grate of the gas-producer 6 where said air is utilized for the genera- 35 tion of the producer-gas.

In the form of the invention illustrated in Figs. 3 and 4, the hot producer-gas flows through the gas-line 7 to the electrical dust precipitator 53 in which said gas flows in 40 counter-current with water-charged air that is conducted from the air-saturator tower 39 through the air-line 47 to said dust-precipitator 53. In the electrical dust precipitator 53, the water-charged air is super- 45 heated, and thence the superheated air flows through the air-line 61 to the grate of the producer 6. Before the air enters the dust-precipitator 53, it is charged with steam from the steam line 52. Otherwise the 50 process illustrated diagrammatically in Figs. 3 and 4 inclusive is the same as that previously described.

Figs. 5 and 6 illustrate diagrammatically a process substantially identical with that 55 disclosed in Figs. 3 and 4 with the exception that the evolved producer-gas flows through a dust-catcher 54 in counter-current with the water-charged air instead of through an electrical dust precipitator. In the dust- 60 catcher, the speed of the gas is reduced somewhat, whereupon the dust particles which pass over with the gas from the producer drop out from the gas and are precipitated in the bottom of the dust-catcher. 65 In the form of the invention illustrated

diagrammatically in Fig. 7, the hot producer-gas passes through the gas-line 7 to a dust-catcher 54 in which it flows in counter-current with the water-charged air that is going to the producer. The air, to which a portion of steam may be added, enters the dust-catcher 54, through the air-line 47 and passes highly superheated to the grate of the producer 6 through the air-line 61. From the dust-catcher 54, the partially-cooled producer-gas, after having been freed of particles of dust and other foreign matter in its current, passes through the gas-line 12 to an electrical dust precipitator 55, in which the gas is freed of any remaining dust or other foreign matter. Thence the dust-free producer-gas passes through the gas-line 56 to a cooler 57 in which it flows in counter-current with cooling water that enters such cooler through the water-line 59 and discharges therefrom through the drain-line 60. In the cooler 57, the gas is cooled to about 90° C., and, at such temperature, the tar, approaching the character of a finely comminuted mist, has begun to be precipitated; and tar so precipitated in the cooler, is discharged through the tar-line 14 into a tar tank 15. From the cooler 57, the gas then flows through a gas-line 58 to the electrical tar-precipitator 18, the process continuing in substantially the manner described in connection with Figs. 1 and 2.

The processes of the invention may be practised in various ways, other than the particular embodiment that has been described for purposes of illustration, and still be within the scope and subject matter of the claims hereinafter made.

I claim:

1. In a process for the recovery of tar and ammonia from producer-gas, the combination of steps that consists in: cooling the hot gas from the producer by passing it in counter-current with water to generate steam and concurrently electrically precipitating the dust from said gas, then further cooling said gas with water; then electrically precipitating the tar from the gas and concurrently reheating said gas; then absorbing the ammonia from the dust-free and tar-free producer-gas by passing such gas through an acid-wash, and concurrently utilizing the heat residuum of the gas to effect deposition of the ammonium sulfate from the ammonia-charged acid-solution; passing the ammonia-free gas through final cooling and dehydrating stages; heating and charging the air going to the gas-producer, with water-vapor, by passing such air in counter-current with the hot water from the first-stage of the aforesaid final cooling of the gas; conveying the water from said air heating operation back to the first stage of the final gas cooling; further charging the

105

110

115

120

125

130

air from the aforesaid air-heating and water vapor charging operation with steam generated in the aforesaid dust-precipitation operation; then again heating the air and 5 conveying it to the gas-producer; substantially as specified.

2. In a process for the recovery of tar and ammonia from producer-gas, the combination of steps that consists in: cooling the hot 10 gas from the producer by passing it in counter-current with water to generate steam and concurrently electrically precipitating the dust from said gas; then further cooling said gas with water; then electrically precipitating the tar from the gas and concurrently 15 reheating said gas; then absorbing the ammonia from the dust-free and tar-free producer-gas by passing such gas through an acid-wash, and concurrently 20 utilizing the heat residuum of the gas to effect deposition of the ammonium sulfate from the ammonia-charged acid-solution; passing the ammonia-free gas through final cooling and dehydrating stages; heating 25 and charging the air, going to the gas-producer, with water-vapor, by passing such air in counter-current with the hot water from the first-stage of the aforesaid final cooling of the gas; conveying the water 30 from said air heating operation back to the first stage of the final gas cooling; further charging the air from the aforesaid air-heating and water vapor charging operation with steam generated in the aforesaid dust-precipitation 35 operation; then again heating the air with waste gas and conveying it to the gas-producer; substantially as specified.

3. In a process for the recovery of tar and ammonia from producer-gas, the combination of steps that consists in: cooling the hot 40 gas from the producer by passing it in counter-current with water to generate steam and concurrently electrically precipitating the dust from said gas; then further cooling said gas with water; then electrically precipitating the tar from the gas; then absorbing the ammonia from the dust-free and tar-free producer-gas by passing such gas through an acid-wash, and concurrently utilizing 45 the heat residuum of the gas to effect deposition of the ammonium sulfate from the ammonia-charged acid-solution; passing the ammonia-free gas through final cooling and dehydrating stages; heating and charging 50 the air going to the gas-producer with water-vapor, by passing such air in counter-current with hot water from the first-stage of the aforesaid final cooling of the gas; conveying the water from said air heating 55 operation back to the first stage of the final gas cooling; further charging the air from the aforesaid air-heating and water vapor charging operation with steam generated in the aforesaid dust-precipitation operation; then again heating the air and conveying it 60

to the gas-producer; substantially as specified.

4. In a process for the recovery of tar and ammonia from producer gas, the combination of steps that consists in: cooling the hot 70 gas from the producer by passing it in counter-current with water to generate steam and concurrently electrically precipitating the dust from said gas; then further cooling said gas with water; then electrically precipitating the tar from the gas; then absorbing the ammonia from the dust-free and tar-free producer-gas by passing such gas through an acid-wash, and concurrently utilizing 75 the heat residuum of the gas to effect deposition of the ammonium sulfate from the ammonia-charged acid-solution; and charging the air going to the gas-producer with the steam generated in the aforesaid dust-precipitation operation; substantially as specified.

5. In a process for the recovery of tar and ammonia from producer-gas, the combination of steps that consists in: cooling the hot 90 gas from the producer by passing it in counter-current with water to generate steam, precipitating the dust from said gas; then further cooling said gas with water; then precipitating the tar from the gas; then absorbing the ammonia from the dust-free 95 and tar-free producer-gas by passing such gas through an acid-wash, and concurrently utilizing the heat residuum of the gas to effect deposition of the ammonium sulfate from the ammonia-charged acid-solution; and charging the air going to the gas-producer with the steam generated in the aforesaid first water-cooling of the gas; substantially as specified.

6. In a process for the recovery of tar 105 and ammonia from producer-gas, the combination of steps that consists in: cooling the hot gas from the producer by passing it in counter-current with water to generate steam, precipitating the dust from said gas; then further cooling said gas with water; then precipitating the tar from the gas; then absorbing the ammonia from the dust-free 110 and tar-free producer-gas by passing such gas through an acid-wash, and concurrently utilizing the heat residuum of the gas to effect deposition of the ammonium sulfate from the ammonia-charged acid-solution; charging the air going to the gas-producer with the steam generated in the aforesaid first water-cooling of the gas; then superheating said air before it reaches the 115 gas-producer; substantially as specified.

7. In a process for the recovery of tar and ammonia from producer-gas, the combination of steps that consists in: cooling the hot 120 gas from the producer by passing it in counter-current with water, precipitating the dust from said gas; then further cooling said gas with water; then precipi- 125

130

tating the tar from the gas; and absorbing the ammonia from the dust-free and tar-free producer-gas by passing such gas through an acid-wash, and utilizing the 5 heat residuum of the gas to effect deposition of the ammonium sulfate from the ammonia-charged acid-solution; substantially as specified.

8. In a process for the recovery of tar and 10 ammonia from producer-gas, the combination of steps that consists in: cooling the hot gas from the producer by passing it in counter-current with water and thereby generating steam, precipitating the dust from 15 said gas; then precipitating the tar from the partially-cooled gas; conducting the aforesaid steam to the air that is on its way to the gas producer; and then conducting the dust-free and tar-free producer- 20 gas through an ammonia absorbing operation; the ammonia recovery from the dust and tar-free gas in the ammonia absorbing operation being augmented by the addition to the air going to the producer of the steam 25 generated in the aforesaid cooling operation; substantially as specified.

9. In a process for the recovery of tar and ammonia from producer-gas, the combination of steps that consists in: cooling 30 the hot gas from the producer by passing it in counter-current with water and thereby generating steam, precipitating the dust from said gas; then precipitating the tar from the partially-cooled gas; conducting the aforesaid steam to preheated and water 35 charged air that is on its way to the gas producer; further heating the steam and water charged air and conducting it to the producer; and then conducting the dust-free and tar-free producer-gas through 40 an ammonia absorbing operation; the ammonia recovery from the dust and tar-free gas in the ammonia absorbing operation being augmented by the addition to the air 45 going to the producer of the steam generated in the aforesaid cooling operation; substantially as specified.

10. In a process for the recovery of tar and ammonia from producer gas, the combination of steps that consists in: subjecting the 50 hot gas from the producer to a primary cooling operation by passing such gas in counter current with water and thereby generating steam; removing the tar and ammonia from such gas; and mixing the aforesaid steam with the air going to the gas-producer; the ammonia recovery from the gas being augmented by the addition to the air going to the producer of the steam generated in the 55 aforesaid cooling operation; substantially as specified.

11. In a process for the recovery of tar and ammonia from producer-gas, the combination of steps that consists in: concur- 60 rently cooling and precipitating the dust

from the hot gas from the producer; then further cooling and washing said gas with water; then electrically precipitating the tar from such partially cooled, but still hot gas; and then passing such still hot gas through 70 an acid wash to absorb the ammonia; substantially as specified.

12. In a process for the recovery of tar and ammonia from producer-gas, the combination of steps that consists in: subjecting 75 the hot gas from the producer to change in speed to precipitate the dust therefrom; then further cooling and washing said gas with water; then electrically precipitating the tar from such partially cooled, but still 80 hot gas; and then passing such still hot gas through an acid wash to absorb the ammonia; substantially as specified.

13. In a process for the recovery of tar and ammonia from producer-gas, the combination of steps that consists in: concurrently 85 cooling and precipitating the dust from the hot gas from the producer; then further cooling and agitating said gas with water; then electrically precipitating the 90 tar from such partially cooled, but still hot gas; and then passing said still hot gas through an acid wash to absorb the ammonia; substantially as specified.

14. In a process for the recovery of tar 95 and ammonia, from tar and ammonia charged gas, the combination of steps that consists in: concurrently cooling and precipitating the dust from the tar and ammonia charged gas; then further cooling 100 and washing said gas with water; then electrically precipitating the tar from such partially cooled, but still hot gas; and then passing such still hot gas through an acid wash to absorb the ammonia; substantially 105 as specified.

15. In a process for the recovery of tar and ammonia, from tar and ammonia charged gas, the combination of steps that consists in: concurrently cooling and subjecting the tar and ammonia charged gas to 110 change in speed to effect precipitation of the dust therefrom; then further cooling and washing said gas with water; then electrically precipitating the tar from such partially cooled, but still hot gas; and then passing such still hot gas through an acid wash to absorb the ammonia; substantially 115 as specified.

16. In a process for the recovery of tar 120 and ammonia, from tar and ammonia charged gas, the combination of steps that consists in: concurrently cooling and precipitating the dust from the tar and ammonia charged gas; then electrically precipitating the tar from such partially cooled, but still hot gas; and then passing such still hot gas through an acid wash to absorb the ammonia; substantially as specified.

17. In a process for the recovery of tar 130

- and ammonia from producer-gas the combination of steps that consists in: concurrently cooling and precipitating the dust from the hot gas from the producer; then 5 electrically precipitating the tar from such partially cooled, but still hot gas; and then passing such still hot gas through an acid wash to absorb the ammonia; substantially as specified.
- 10 18. In a process for the recovery of tar and ammonia from producer-gas, the combination of steps that consists in: subjecting such gas to a cooling operation; precipitating the dust from the gas; concurrently precipitating the tar from the gas and reheating 15 said gas; and then directly effecting the precipitation of ammonium sulfate, by passing such gas through an acid-wash; the ammonia being absorbed from the gas by the acid-solution and the gas acting as the carrier for the evaporation from the acid-solution through which the gas passes; substantially as specified.
19. The process for the recovery of tar and ammonia from producer-gas, which 25 consists in, extracting the tar from hot dust-free producer-gas, and passing said gas directly from such tar-extraction to and through a sulfate acid wash, while said gas 30 still retains sufficient super-heat to effect deposition of the ammonium-sulfate from said bath, substantially as specified.
20. In a process for the recovery of tar and ammonia from producer-gas, the combination of steps that consists in: subjecting 35 the hot gas from the producer to a primary cooling operation by passing it in counter-current with the air that is going to the producer, and concurrently precipitating the dust from said gas; then electrically precipitating the residue of the dust from said gas; then further cooling said gas by passing it in counter-current with water; then electrically precipitating the tar from the gas; then absorbing the ammonia from the dust-free and tar-free producer-gas by passing such gas through an acid-wash and concurrently utilizing the heat residuum of the gas to effect deposition of the ammonium sulfate from the ammonia-charged acid-solution; passing the ammonia-free gas through final cooling and dehydrating stages; heating and charging the air going to the gas-producer, with water-vapor, by passing such air in counter-current with the hot water from the first-stage of the aforesaid final cooling of the gas; conveying the water from said air-heating operation back to the first stage of the final gas cooling; further charging the air from the aforesaid air-heating and water-vapor charging operation with steam; and then conveying the air to the aforesaid primary gas-cooling operation; substantially as specified. 45
21. The process for the recovery of tar and ammonia from producer-gas, which consists in: subjecting such gas to a cooling operation, precipitating the dust from the gas, precipitating the tar from the gas, reheating the gas, and then directly effecting the precipitation of ammonium sulfate, by passing such gas through an acid wash; substantially as specified. 50
22. The process for the recovery of tar and ammonia from producer-gas, which consists in: subjecting such gas to a cooling operation, precipitating the dust from the gas, precipitating the tar from the gas, and then directly effecting the precipitation of ammonium sulfate, by passing such gas through an acid wash, the ammonia being absorbed from the gas by the acid-solution and the gas acting as the carrier for the evaporation from the acid-solution through which the gas passes; substantially as specified. 55
- In testimony whereof I have hereunto set my hand this 15th day of August, 1919.
- JOSEPH BECKER.
